TONE ARM

Roy Dally, Racine, Wis., assignor to Webster Electric Company, Racine, Wis., a corporation of Delaware

Application October 16, 1942, Serial No. 462,277

1 Claim. (CL 274-1)

The present invention relates to tone arms and is particularly concerned with the provision of an improved device for holding the tone arm in fixed position adjacent the turntable when it is not being used.

One of the objects of the invention is the provision of an improved tone arm support construction by means of which the tone arm may be most conveniently mounted in a fixed relation to its support adjacent the turntable whenever it is not being used.

Another object of the invention is the provision of an improved tone arm support of the class described which is sturdy, capable of being manufactured at a low cost and adapted to hold the tone arm securely and to release it when desired.

Another object of the invention is the provision of an improved tone arm and tone arm support construction in which the channel construction of the tone arm is used for engaging a compressible support by means of friction in such manner that it may be forced on the support and forcibly removed without necessity for providing any latches.

Other objects and advantages of the invention will be apparent from the following description and the accompanying drawing in which similar characters of reference indicate the same parts throughout the several views.

Referring to the single sheet of drawings,

Fig. 1 is a fragmentary plan view of a tone arm carried by a support and provided with a turntable and an auxiliary supporting member constructed according to the invention;

Fig. 2 is a bottom plan view of the tone arm; and

Fig. 3 is a fragmentary sectional view taken on the plane corresponding to the line 3-3 of Fig. 1 and looking in the direction of the arrows showing the details of the construction of the auxiliary support when the tone arm is supported on it.

Referring to the drawing, 10 indicates the support for the turntable and tone arm which may consist of the top panel of a phonograph housing. The top panel 10 is provided with a suitable column 11 adapted to support the tone arm 12 at the left end of Fig. 1 for a limited universal movement. The tone arm 12 is adapted to pivot laterally on the column 11 to follow the groove in the record, and it is also adapted to pivot upward on a horizontal axis so that the tone arm may be lifted from the record or placed upon it.

The tone arm 12, which is shown in bottom plan in Fig. 2, is preferably of a channelled construc-

tion comprising a top flange 13 and a pair of side flanges 14, 15. It may contain any kind of pickup or cutting mechanism at its free end and the crystal pickup 15 is merely exemplary of one type of reproducing mechanism carried by the tone arm. The crystal pickup 15 is provided with a check 16 carrying a stylus 17. The conductors 18 and 19 from the crystal pickup 15 extend longitudinally of the interior of the channelled tone arm 12 to the fixed connectors 20, 21. The side flanges 14 and 15 preferably extend around the full outer wall of the tone arm, but the bottom of the tone arm is preferably open and the flanges 14 and 15 are preferably relatively thick at the intermediate part of the arm where they are adapted to engage the auxiliary support 22. The auxiliary support 22 is shown in detail in Fig. 3, and it comprises a column carried by the panel 10 and adapted to support the tone arm in its fixed position. This column may consist of a screw bolt 23, the head 24 of which is preferably of the countersunk type provided with a slot 25 for a screw driver, and the lower threaded end 26 of which is engaged by a washer 27 and nut 28. Bolt 23 passes through a bore 29 in panel 10. It also passes through a tubular member 30, which may be made of metal or suitable insulating material such as a phenolic condensation compound.

The tubular member 30 has a through bore 31 for passing the screw bolt 23. Its lower end 32 is preferably plane so as to engage the panel 10 and to provide a suitable base. The lower end portion 33 is enlarged to provide a larger area for the end or base surface 32.

At its upper end the tubular member 30 may also have a plane surface 34 for engaging the resilient compressible head 35. The resilient compressible head 35 comprises a substantially cylindrical member of resilient rubber or other suitable resilient material such as a printer's roll composition. It has an axial through bore 36 for passing the screw bolt 23, and has a countersunk depression 37 for receiving the head 24 of the screw bolt. Its upper corners 38 are preferably rounded to provide a tapered surface adapted to enter between the flanges 14 and 15 of the tone arm more readily.

The resilient head 35 is fixedly supported on the column 22 by means of the bolt 23 and tubular member 30. It is preferably located on the panel 10 opposite the turntable 39 and slightly spaced from the turntable in such a position that the tone arm may be lifted from the

record and it may have its channel brought into registry with the top of the head 35 and then the tone arm may be forced down upon the head 35. The flanges 14 and 15 then compress the head 35 as the head 35 passes between the flanges, and the tone arm is frictionally engaged on the head. It may be removed from the auxiliary support 22 by merely lifting it and overcoming the friction which holds it on the head, but the friction is sufficient to support the weight of the tone arm when the phonograph is inverted. Furthermore, the height of the column 22 may be made such that when the tone arm is carried by the auxiliary support 22, its upper flange 13 is just below the cover of the phonograph which is secured by a suitable lock so that the tone arm cannot come off the auxiliary support 22.

It will thus be observed that I have invented an auxiliary support for tone arms which is adapted to receive the tone arm and hold it when the tone arm is merely pressed upon it. The height of the column is such that the needle is always held out of contact with the panel or turntable or record, and the column may also be made of such height that the tone arm is carried immediately below the cover of the phonograph so that it cannot be accidentally dislodged from its auxiliary support. This auxiliary support may be constructed at a low cost; it is sturdy and capable of being used for a long period of time without repair. It is convenient because it is only necessary to push the tone arm down upon it when it is to be secured on the support, and it is only necessary to pull the tone arm off when it is to be used.

The head 35, being of cylindrical shape, does not affect its operation if it should rotate slightly upon the supporting bolt 23, as it is always in proper position to be engaged by the tone arm. The rotation of the head permits

new surfaces to be brought into engagement with the tone arm and enables the user to compensate for any wear that takes place.

Since the head 35 is of compressible material, it may be expanded laterally by means of the threaded member 23 and tubular member 30 which are adapted to place a compression on the end surfaces of the cylindrical member 35 to expand it into a larger diameter and into 10 better frictional engagement with the tone arm whenever necessary.

While I have illustrated a preferred embodiment of my invention, many modifications may be made without departing from the spirit of 15 the invention, and I do not wish to be limited to the precise details of construction set forth, but desire to avail myself of all changes within the scope of the appended claim.

Having thus described my invention, what I 20 claim as new and desire to secure by Letters Patent of the United States, is:

In a phonograph, the combination of a supporting panel with a column for supporting a tone arm, an auxiliary support for the free end 25 of said tone arm, comprising a tubular supporting member having an enlarged base for engagement with the supporting panel, a resilient enlarged head mounted on the upper end of said tubular supporting member, and a threaded member passing through said head and said tubular supporting member and through said panel, and having threaded means 30 for drawing said head and tubular supporting member against said panel, said resilient head being of a size adapted to be received between opposed depending portions of said tone arm, and said threaded member exerting a predetermined compression on said resilient head to 35 regulate its distortion into predetermined size 40 for engagement with the tone arm.

ROY DALLY.
